UNITED STATES PATENT OFFICE

2,489,120

HAIR CURLER

Anne S. Carlin, Los Angeles, Calif.

Application April 22, 1947, Serial No. 743,008

2 Claims. (Cl. 132—40)

1

The present invention relates to improvements in hair curlers for permanent waving known as the cold wave process.

An important object of the invention is to provide in a device of the above character improved means for keeping the formed curl away from the scalp in order that the solution employed in setting the curl will not contact the scalp, thereby eliminating any cause for irritation. This is especially important when the hair on the head is thin.

Another object is to provide improved means for initially connecting the curling device to the lock of hair preparatory to winding the lock on the curling portion and subsequently using such connecting means to secure the ends of the lock strands in a fixed relation after the curling operation has been performed.

Another and more specific object is to provide as an article of manufacture a hair curling cylinder, and twisted lengths of insulated wire projecting from opposite ends of the cylinder whose raw ends are concealed within the cylinder.

A still further object of the invention is to provide a hair curler of the type described which may be, upon sterilization, used over and over again.

Yet a further object of the invention is to provide a hair curler by means of which the hair may be curled using the cold wave process in an improved manner.

Other objects, features and advantages of invention will hereinafter appear.

Referring to the drawings wherein is shown a preferred embodiment of the invention,

Fig. 1 is an elevational view of the coated wire per se.

Fig. 2 is an elevational view similar to Fig. 1 except that the folded portions in Fig. 1 are shown twisted in Fig. 2.

Fig. 3 is an elevational view of the improved curler wherein the raw ends of the wires shown in Fig. 2 are, with adjacent portions of the twisted loops, concealed within a hair curling tube.

Figs. 4-8 are elevational views showing the consecutive steps involved in a hair curling operation.

Referring in detail to the drawing, the single strand of wire 10 in Fig. 1 is bent or folded upon itself at one side of its midlength portion to provide a folded portion 11 and each of the free end portions of the wire 10 is bent or folded upon itself to provide a long length folded portion 12 and a shorter length folded portion 13. Folded part 11 is twisted to form twisted length 14 and

2

folded parts 12 and 13 are twisted to form respectively twisted lengths 15 and 16.

17 indicates a hair curling sleeve or cylinder into which the twisted length 14 is projected and 5 then pulled through to securely position the raw ends 10a and 10b of the wire 10 in a concealed friction-like manner near the midlength of the sleeve to prevent the head of the person having her hair curled from being injured. Said raw ends tend to bite into said sleeve and securely hold the wire structure against sliding out therefrom.

The first operational step, as shown in Fig. 4, 15 consists in placing the lock of hair 18 in the crotch 19 formed by the wire runs 15 and 16 at the upper end of the sleeve and then twisting said runs together to hold the sleeve in position adjacent the lock 18 preparatory to winding the latter around the sleeve.

20 The second step in the operation of curling, as shown in Fig. 5, consists in spirally winding the lock of hair 18 around the sleeve 17 and holding the loose end by the little finger 20 preparatory to placing wool crepe around the ends of the lock.

25 The third step in the operation of curling, as shown in Fig. 6, consists in winding the wool crepe 21 around the loose strands of hair at the end of the lock incident to untwisting the short twisted length 16 from the long twisted length 15 for the purpose of freeing the latter length so 30 that it may be bent downwardly and have its free end portion wound around the crepe wool 21.

35 The fourth step in the operation of curling, as shown in Fig. 7, consists in untwisting the short twisted length 16 from the long twisted length 15 and then bending the long length 15 downwardly and coiling the free end 22 thereof around the crepe wool 21 to keep the formed curl from uncurling. Thereupon the short length 16 is directed 40 downwardly along the side of the uncurled part of the lock of hair to prevent the sheath 17 from turning in a direction tending to uncurl the lock of hair.

45 The fifth step (an optional step) in the operation of curling, as shown in Fig. 8, consists in bending the twisted length 14 toward the subject's head thus forming a prop for supporting the sleeve 17 in an outwardly spaced relation to the head to keep the curling solution from contacting the scalp. When this is done the wire 14 should have its terminal portion deflected at 50 25 to prevent the end of the wire from irritating the scalp.

55 After the time allotted for the curl on the sleeve to be permanently set the wire end 22 is un-

wound from the wool crepe 21, the wool crepe removed, and the device detached from the curl.

I claim:

1. In a device for cold wave hair curling, a sleeve upon which to spirally wind the hair, a folded length of wire whose end portions are in turn folded back part way upon themselves to form two folded over portions which are opposite said single folded over portion, said single folded over portion and said two folded over portions being twisted throughout their lengths to form two twisted lengths which are opposite the single twisted length all of which combine to form an article having a Y shape, the raw ends of the wire being located at a point adjacent the 15 crotch in the Y, said Y shape extends into said sleeve to a point wherein said raw ends are concealed within and tend to bite into said sleeve, thus internally anchoring the wire structure to said sleeve.

2. In a device for cold wave hair curling, a folded length of single wire whose end portions

are in turn folded back part way upon themselves to form two folded over portions of unequal length which are at that end of the structure which is opposite to said folded over single wire portion, said folded over single wire portion and said two folded over portions being twisted throughout their lengths to form two twisted lengths which are opposite to the single twisted length, all of which combine to form an article having a Y shape wherein the stem of the Y consists of a single pair of twisted together wire runs.
